Primary Examiner — Catheri Oliver-Garcia*(74) Attorney, Agent, or Firm* — Duane Morris LLP; J. Rodman Steele, Jr.; Gregory M. Lefkowitz**(57) CLAIM**

The ornamental design for an air gun holder pouch, as shown and described.

DESCRIPTION

FIG. 1 is a front perspective view of the air gun holder pouch showing the new design;
 FIG. 2 is a front elevation view thereof;
 FIG. 3 is a rear elevation view thereof;
 FIG. 4 is a left side view thereof;
 FIG. 5 is a right side view thereof;
 FIG. 6 is a top plan view thereof;
 FIG. 7 is a bottom plan view thereof; and,
 FIG. 8 is an environmental, perspective view of the ornamental design with an air gun attached thereto.

The broken lines depicting environmental structure are for illustrative purposes only and form no part of the claimed design.

The design is shown broken away in the drawings to indicate that no particular length is claimed.
